UNITED STATES PATENT OFFICE

WILLIAM R. HEWITT, OF NEW YORK, N. Y.

RAILWAY TIE-PLATE

Application filed September 3, 1929. Serial No. 890,110.

My present invention relates to a metallic railway tie plate and means for fastening and holding a rail in position on a railway tie.

The object of this invention is to provide an improved metallic seat for the rail in order that the railway cross tie may be protected as fully as possible from the injurious effects due to the working of the rail on its seat in the passing of traffic over the rails which causes more or less wear and tear on the wood tie.

The use of a metallic tie plate is quite common and generally recognized as necessary in railroad practice today. Its object being to prolong the life of the wood tie. The ideal condition for prolonging the life of the wood tie would consist in providing such protection to the tie as would effect a minimum wear and tear. Deterioration of the tie is largely due to the use of spikes in fastening the rails through the tie plate to the tie. Primarily the use of the spike distorts the wood fiber in the tie and as the traffic develops quite often the spike is loosened from the position of its original fastening with the result that its effectiveness as a means of holding down the rail is practically destroyed.

Having this view of the conditions developed in connection with the fastening of rails to the tie I have provided a tie plate which will overcome these faults and maintain the rail in its position as laid for a longer period of time than can be done by the usual methods now prevailing.

My invention reduces the penetration of the wood tie to a minimum and affords a means of holding the rails whereby the wood of the tie suffers a minimum of mutilation, and further by the use of my improvement the gauge of the rails is maintained constant at all times. The laying of the rail is facilitated in that it may be put in position with the least amount of adjustment and the

rail can be removed readily from the tie plate without disturbing the tie conditions under which it was laid.

Further advantages of this invention are that it will prevent the slewing of the ties and will act effectively as a means for preventing creeping of the rails. The construction and design are such that the plate may be weatherproofed and will hold its original shape for a maximum period of time, and the plate can be made of lighter material than other types of plates heretofore provided and therefore can be manufactured in quantities at less cost than can ordinary types of tie plates now in common usage.

A preferred embodiment of my invention is set forth in the following specifications and accompanying drawings by way of illustration and not of limitation.

In these drawings—

Figure 1 is a perspective view of a portion of a railroad tie showing my improved tie plate in position thereon and indicating the position of the rail on the tie plate.

Figure 2 is a side elevation of the tie plate showing a cross section of the rail in position thereon, and

Figure 3 is a plan view of the plate as shown in Figure 2.

Similar numerals refer to similar parts throughout the several views.

In the drawing, 10 designates a portion of a wooden tie of the kind commonly used in railroad construction. Mounted upon the tie, there is shown a tie plate 11. This tie plate 11 is adapted, as illustrated, to extend along the top of the tie at the point where the rail engages therewith. The tie plate is illustrated as having an inwardly extending tongue or projection which projects centrally along the tie and at its innermost end there is provided a means 12 which may be a bolt, a lag screw, or ordinary spike for securing the tie plate in position and against displacement upon the tie.

In the drawing a washer 13 is shown as co-operating with the bolt 12 in order that the plate may be drawn tightly against the tie. At the point where the rail engages the tie plate 11 there is provided a pair of distance or limit plates 14 which are secured thereto on each side of the rail flanges and act as guides for the rail setting and to maintain a constant gauge of the rails as will hereinafter appear.

Specially designed rivets 15 are shown as being secured to the tie plate 11 and extending through holes in the limit or distance plates 14. The heads of these rivets are provided with flat sides so that the rivets may with the use of a suitable wrench be turned through 180° in either direction. The heads of the rivets are eccentrically positioned in relation to their body portion so that turning the head will cause it to assume different positions in relation to the distance plates 14 and rails 17. The rivets shown at 15 are in their normal position for locking the rails 17 against the tie plate 11 and the rivets shown at 16 have been turned through 180° to a position so that the rail 17 may be conveniently raised from its seat without disturbing the position of the tie plate attached to the wood tie. The lower rounded ends of the rivets extend below the lower surface of the tie plate where they bear upon the tie and serve as calks to prevent slippage of the plate upon the tie. The tie plate 11 has its side edges bent downwardly to an angle of 90° forming flanges 18 designed to fit over the sides of the tie, these flanges serving to prevent the tie from slewing beneath the rails and in addition reinforce the tie plate immediately under the rail and act in combination with the rivets 15 to prevent the rails from creeping.

While certain features of the present invention are more or less specifically described, it should be understood that various changes of the design may be resorted to without departing from the spirit and scope of the appended claims.

Having thus described my invention, what I claim and desire to secure by Letters Patent is—

1. A tie plate of the character described comprising a main plate portion adapted to support a rail, an inwardly extending portion formed integral with said main portion adapted to be secured to the tie at a point between the rails, and limit plates upon said main portion adapted to co-operate with the rail holding means to prevent movement of said rail longitudinally of the tie.

2. A tie plate comprising a main plate portion having its edges bent downwardly to conform to the top of a railway tie, limit plates to engage a railway rail, a holding bolt to secure said tie plate to said tie, and

rivets for holding said rail in close engagement with the tie plate, said rivets being journaled in the tie plate and having heads eccentrically disposed so that turning of the rivets causes their engagement and disengagement with the rail as desired. 70

3. A tie plate of the character described comprising means for securing the tie plate to a tie whereby vertical movement of a rail supported by said tie plate will not 75 cause damage or deterioration of said tie, means carried by said tie plate for preventing longitudinal movement of said rail in relation to said tie, and means having eccentrically disposed heads for securing said 80 rail to said tie plate.

4. In a rail mounting the combination of a tie plate having a body portion with its edges bent downwardly to engage the sides of a tie, a single holding bolt adapted to 85 pass through a hole in one end of said body portion and secure said tie plate to said tie, limit plates secured to the upper surface of said body portion adapted to engage the outer edges of the flange of a rail, and means 90 consisting of specially designed rivets extending through holes in said tie plate and said limit plates for securing said rail in close engagement to said tie plate.

5. In a rail mounting the combination of 95 a tie plate having a main body portion adapted to engage the top and upper edges of a railway tie, a holding adapted to pass through a hole in one end of said body portion and secure the same to said tie, limit 100 plates fastened to the upper surface of said tie plate and engage the outer edges of the flange of a rail, and means for detachably securing said rail to said tie plate, said means consisting of rivets extending 105 through holes in the tie plate and limit plates having eccentrically disposed heads on their upper ends so that turning of said rivets will cause their engagement and disengagement with the rail as desired. 110

6. The combination with a rail and a tie forming a support therefor, of a tie plate interposed between the tie and the rail, means securing the tie plate to the tie, a plurality of rotatable bolts carried by the tie plate and disposed on opposite sides of the foot flange of the rail, and eccentric heads on said bolts movable into and out of engagement with the foot flange of the rail. 115

7. The combination with a rail and a tie forming a support therefor, of a tie plate interposed between the tie and the rail, a pair of limit plates mounted on the tie plate, one on each side of the foot flange of the rail and engageable therewith, a pair of bolts 120 extending through the tie plate and the limit plates and securing the limit plates against removal from the tie plate, said bolts being free to rotate with relation to the tie plate and the limit plates, an eccentric head on 125

each bolt movable into and out of engagement with the foot flange of the rail, and means whereby the tie plate is secured to the tie.

- 5 8. The combination with a rail and a tie forming a support therefor, of a tie plate interposed between the tie and the rail, a pair of limit plates mounted on the tie plate, one on each side of the foot flange of the rail and engageable therewith, means cooperating with the limit plates to secure the rail against removal from between the limit plates, and other means to secure the tie plate to the tie.
